BAG MAKING MACHINE

Adolph Potdevin, Garden City, N. Y., assignor to
 Potdevin Machine Company, Brooklyn, N. Y.,
 a corporation of New York

Application March 14, 1935, Serial No. 10,968

26 Claims. (Cl. 93—22)

The present invention is directed to an improved method and apparatus for making bags, and has for one of its objects the provision of an improved method and construction whereby bags of the satchel bottom type may be expeditiously and economically made of cellulose or other light weight materials.

Those skilled in this art will appreciate the difficulty experienced in the making of bags from these materials by automatic machinery.

The present invention is directed primarily to the bottoming mechanism. The tubes from which the bags are to be made and which have a projecting lip at their leading end are fed to my improved bottom folding mechanism in any conventional manner.

In the accompanying drawings:

Fig. 1 is a sectional elevational view of my improved bottom forming mechanism;

Fig. 2 is an enlarged view of improved scoring mechanism employed in the present invention;

Fig. 3 is a view of a bag length after it has been slit at the lip or leading end and as it appears after being scored by the scoring mechanism of

Fig. 2;

Fig. 4 is a plan view of Fig. 1;

Fig. 5 shows a bag length partially opened at the bottom end in the first stages of bottoming;

Fig. 6 illustrates the next step in the bottoming of the bag length;

Fig. 7 is a view on a somewhat enlarged scale showing the position of certain parts of the bottoming mechanism in the later stages of the bottoming operation;

Figs. 8 and 9 show further stages in the bottoming operations;

Fig. 10 is a plan view of the bottoming drum partially broken away to show some of the internal construction;

Fig. 11 is a view on a somewhat enlarged scale of one of the gripper rollers which engages or grips the leading end of the bag length as the same comes up to the bottoming drum;

Fig. 12 shows the completed bag;

Fig. 13 is a part sectional elevational view of another form of cross scoring mechanism; and

Fig. 14 is an elevational view of the same mechanism.

Attempts to make so-called satchel bottom bags from regenerated cellulose or other light materials on rotary machines heretofore used exclusively for making the same style of bag from ordinary bag paper have not met with much success. The machine of the present invention is well adapted for this purpose enabling satchel

bottom bags to be made with great accuracy and at very high speeds.

Referring to the drawings in detail, it is to be understood that the material to be handled by the present apparatus is taken from a roll in the usual fashion and fed through usual tubing mechanism which forms the web into a tube. The tubed material designated 1, and which it will be understood is being advanced continuously and in a continuous length, is divided into bag lengths by the mechanism shown at 2 which may be of any conventional construction, but here shown as similar to the cutting off mechanism constituting the subject matter of Paul Hunziker copending application Serial No. 647,502. This cutting-off mechanism 2 cuts the tubing into bag lengths, leaving a lip 3 at the leading end of the bag length or bag blank and a lip 4 at the trailing end as shown in Fig. 3, for example. A bag length is shown in Fig. 3 and has been designated 5.

During the cutting off operation the tubing is engaged by pinch rollers 6 and 7 and lies at this time between the upper face of a plate 8 and adjustable hold-down fingers 9 which are carried by rods 10 secured to the machine frame. As the tube is divided into bag lengths the leading end of each length passes between slitting and scoring mechanism shown at 11 and 12 in Fig. 1 to slit the leading end of each bag length through both walls thereof as shown at A and B, in Fig. 3 for instance, and to cross score the bag length as shown at CS in the same figure.

In the usual bag machine for converting ordinary bag paper into bags it is customary to equip the machine with a cylinder having a longitudinal groove therein cooperating with a scoring knife in an opposed cylinder so as to cross-score the bag tube for the main bottom fold. Owing to the natural springiness or elasticity of materials such as "Cellophane", for which my machine is particularly well adapted, such cross-scoring mechanism does not score the bag length satisfactorily, and if, in order to obtain a well defined score with such mechanism, the parts are set closer together than when handling ordinary bag paper there is always danger of cutting the material instead of merely scoring it, with a resultant increase in waste.

The present invention provides for eliminating these difficulties.

As clearly shown on the drawings, particularly Figs. 2 and 4, the scoring mechanism comprises a thin scoring blade 13 preferably mounted on a rotarily adjustable shaft 14 carried in discs 15 on a shaft 16. These discs are adjustable cir-

cumferentially of the shaft 16 as will be seen from Fig. 4. The scoring blade which depresses the bag blank or bag length out of the plane of the surface of the blank in a transverse area cooperate with a cam-and-spring operated movable jaw 17 carried by a shaft 18 having bearings in the end walls of circumferentially adjustable disc cylinder 19 mounted below the discs 15 on shaft 19'. The cam and spring for operating the jaw 17 are designated 20 and 21, respectively.

The lower disc cylinder 19 carries an abutment 22 which cooperates with the movable jaw 17, the abutment and jaw constituting compression jaws. The face of the jaw 17 is cut back at an angle as shown in Fig. 2. In operation, the blade 13 depresses the wall of the bag length between the jaw 17 and abutment 22, before the jaw closes, and as on continued rotation of the discs 15 and lower cylinder 19 the blade 13 is withdrawn, it is followed up by the jaw 17, which sharply grips the tucked-in portion of the bag length at the apex 23 only, as shown in Fig. 2, instead of the entire face of the jaw clamping the material between it and the abutment 22 in a manner similar to that employed in clamping devices generally used heretofore for folding paper.

By sharply pinching only the apex 23 of the tucked-in portion of the bag length, I provide a permanent transverse or cross-score CS in the material despite the natural springiness or elasticity of the same. At the same time I avoid cutting of the material so as to eliminate all waste from the cross-scoring operation.

Two of the discs 15 which are adjustable longitudinally of the shaft 16 are provided with slitting knives 24 for slitting the bag lengths at A and B, these slitting knives as will be seen from Fig. 1 being adjustable circumferentially relatively to the shaft 16, and cooperating with lower discs 19, adjustable longitudinally of their supporting shaft 19', so as to adapt the machine for adjustment properly to slit bag lengths of different sizes as will be understood. The slitting operation, as will be seen from Fig. 1, precedes the cross-scoring operation.

During the slitting and scoring operation the bag length underlies adjustable hold-down fingers 25 carried by vertically extending posts 26 mounted on the machine frame.

Inasmuch as there is no other operation to be performed at this point the scoring clamp 17 releases the tube immediately after the cross-scoring operation is completed and the bag tube is forwarded by the rotating scoring mechanism to the next station of operation between discs 27 and cooperating lower cylinder 28, passing between hold-down fingers 25 and plate 29.

As the leading end of the bag length reaches this next station of operation the cam-and-spring operated gripper 30 carried by one of the discs 27 takes hold of the upper ply of the bag length at the point 31, Fig. 3, between the slits A, clamping it against cooperating abutment 32 on the shaft 33 on which the discs 27 are mounted.

As the bag length passes between the discs 27 and the cylinder 28 the gripper 30 will be in open position as shown in Fig. 11 so that the nose of the gripper will enter the open end of the tube and the projecting lip 3 on the lower wall of the tube will be pushed downwardly as illustrated in Fig. 11 bending the same over the edge of an abutment 34 on the shaft 35 carrying the lower cylinder 28, this portion of the lower wall springing back against the back of the gripper 30 as the gripper clamps or grips the upper wall against

the abutment 32. The abutment 34 is adjustable circumferentially of the shaft 35.

Pivotedly mounted on the discs 27 is a shaft 36 carrying a blade 37. One end of this shaft is equipped with a lever and cam follower roller 38 and with a suitable spring 39 to keep this roller in contact with an adjustable stationary cam 40. The function of this cam is to cause the blade 37 to swing outwardly beyond the periphery of the discs 27 at the proper instant to push the scored area of the bag length away from the surface of the discs 27 and toward the large bottom opening drum 41 which carries grippers 52 for gripping the lip 3 as will be presently described. In this way I prevent the bag length from being pulled open beyond the cross-scoring CS.

The gripper 30 heretofore referred to is mounted on a shaft 42 and is controlled by a cam 43.

The hold-down fingers 25, referred to above, extend from a point at the rear of the slitting and scoring station to a point between the discs 27 and cylinder 28.

Between the scoring station and the station just referred to I provide a rock shaft 44 carrying flat spring-like fingers 45 extending forwardly and downwardly between the hold-down fingers 25. The shaft 44 is rocked by a cam 46, cam follower roller 47 carried by the shaft 44 being held in engagement with this cam by a spring 48. The fingers 45 remain in a raised position during the progress of the tube 5 from the scoring station to the gripper or clamping station until the lip 3 on the leading end of the tube has been gripped by the grippers on the bottoming cylinder 41 at which time the cam 46 will be in position to move these spring fingers 45 downwardly toward the lower guide plate 29 to hold the tube with a slight spring pressure against the guide plate, the spring fingers continuing to hold the bag length in contact with this plate approximately until the gripper 30 is ready to release the leading end of the upper ply of the bag length, it being borne in mind that the leading end of the upper ply of the bag length is gripped at this time by gripper 30 as above explained.

The fingers 45, therefore, exert a slight friction hold-back action upon the bag length 5 during the first stages of opening the leading end of the bag length in the bottoming operation, thereby assuring that the bag length 5 will lie flat on the drum 41, so that the previously made score CS, Fig. 3, will always be in the same and correct position for the blade 37 to act on as previously explained.

The shaft 50 carrying the bottoming drum 41 carries a spider 51, equipped with a plurality of center grippers 52 which are adapted to grip the lip 3 at the leading end of the bag length as the tube comes up to the bottoming drum and to clamp this lip against a cooperating abutment 53 carried by the spider. These grippers are spring actuated and cam released, the releasing cam being shown at 54. The spider 51 is adjustable as will be brought out hereinafter.

After the flap 3 at the leading end of the bag length has been gripped by a gripper 52 and the bag length opened sufficiently the gripper 30 releases its hold and the released portion of the bag length is engaged by a stationary curved depending finger 55, thus holding the bag length open without straining it and without tearing the material at the end of the slits A and B, the end of this finger 55 remaining in contact with the upper panel of the bag length until folders 56 descend to flatten the partially open bag length 75

against the drum as shown in Fig. 6. The function of the folders 56 is to fold over and fold down the edges of the bag length as shown at 57 in Fig. 6.

The folders 56 are carried by a short arm 58 adjustably mounted on a rod 59 which through the medium of lever 60 and a cam roller carried thereby and cam 61 is caused to rock in proper timed relation to the release of the bag length 10 by the grippers 30 and to the rotation of the bottoming drum. The folders 56 are curved as will be seen from Fig. 1 of the drawings to the contour of the bottoming drum and are so mounted as to move toward the bottoming drum 41 and 15 in the direction of the advance of the bag length thus folding over the sides of the bag length and flattening the same to the drum without undue strain on the material and without tearing the slits in the same.

20 The bag length which now has been folded as shown in Fig. 6 and which is still being held by center gripper 52 advances to and under a segmental roller 62, where it is subjected to a further ironing or flattening operation. This roller is 25 segmental, as just mentioned, better results being obtained by employing a roller with a broken periphery in that the edges 63 of the in-folded portions 57 of the bag length are allowed to pass the center line of the bottoming drum and of 30 the segmental roller before the ironing or rolling operation begins. If a roller without a broken periphery were employed the edges 63 might be caught thereby and be pushed rearwardly as the bag length is advanced by the bottoming drum 35 thereby deforming the bag bottom. Instead of employing the segmental roller 62 I may employ a full faced roller with means for lifting the same periodically and in proper timed relation to the advance of the bag length so that during 40 the entering period of the bag length between the roller and bottoming drum the roller would be in raised position. I prefer, however, the simple arrangement of a segmental roller.

The bag length now advances to bottom scoring 45 and paste applying mechanism. The bottom scoring mechanism comprises scoring blades 67 and 68 and pairs of score jaws 64 and 65 the latter being carried by an adjustable spider 66 on the bottoming drum shaft 50. The jaws 64 and 50 65 are spring-closed and cam-released. The jaw 64 is released by a cam 69 while the jaw 65 is released by a cam 70.

As a bag length comes up to the bottoming drum the jaws 64 and 65 are being held closed by 55 their respective springs. When the jaws hit the cam 71, however, on continued rotation of the bottoming drum, they are opened again so as to be in open position when they come up to the co-operating scoring blades 67 and 68.

60 As the bag length arrives at the bottoming drum, therefore, lip 3 is first gripped by one of the center grippers 52, the same having moved off its opening cam 54, and the end of the bag length is opened, folded over and pressed down as above described, and arrives at the scoring blades 67 and 68 in the condition shown in Fig. 6, still gripped by center gripper 52. The blade 67 first engages the face of the bag length and forces the same toward the drum between scorer jaw 64 and cooperating abutment 72, which are 65 in position to receive it, and the scorer jaw closes, the scorer jaw at this instant riding off its opening cam 71. On continued advance of the bag length, scorer blade 68 forces the material between the next scorer jaw 65 and its cooperating

abutment 73 which are in position to receive it, and the scorer jaw closes, the jaw at this instant having moved off its opening cam 71.

The bag length thus held to the bottoming drum next passes to an adhesive-applying station 5 where adhesive 75 is applied to the face thereof as shown in Fig. 8.

In its passage from the scoring blades 67, 68 to the adhesive-applying station the tube or bag length passes under hold-down spring fingers 10 15 These fingers or plates as will be seen from Fig. 1 are curved to the contour of the bottoming drum and are adjustable toward and away from each other so as to accommodate bags of different widths.

15 As above mentioned the spider 51 which carries the center grippers 52 and their cooperating abutments 53 is adjustable circumferentially of the shaft 50. This is accomplished by eccentric 19, locking in adjusted position being accomplished by slot and bolt arrangement shown at 20 25 79'. This adapts the machine for bottoms of different widths, as will be understood.

25 It has also been mentioned that the spider 66 carrying the scorer jaws 65 and their cooperating abutments 73 is adjustable circumferentially of the shaft 50. This is accomplished by an eccentric 30 35 39, locking in adjusted position being accomplished by the slot and bolt arrangement 79'. This permits the spacing of the grippers 64 and 65 to be varied to accommodate bottoms of different widths.

30 In the periphery of the bottoming drum, behind each of the scorer jaws 65 I provide an 35 adjustable block 81. This block extends lengthwise of the drum and is made adjustable circumferentially of the drum so as to fill in the space back of the jaws 65 when the latter are adjusted, for a purpose presently to be brought out.

35 The next step is the folding of the rear bottom flap 82, that is to say, the flap extending rearwardly from the scorer 77 made by the scorer jaw 65. This folding is accomplished by a fold-over roller 83 carried by a chain 84 in the fashion 40 corresponding to my prior Patent No. 1,176,163, 45 the roller 83 traveling at a higher speed than the bag tube or bag length. However, due to the springy nature of cellulose material and due to pasting difficulties experienced with such materials I have provided additionally a rear flap 50 follow-up folder 85 the function of which is to engage the rear flap 82 of the bottom before the same is released by the fold-over roller or bar 83. This follow-up folder 85 is carried on an arm 55 60 pivoted on the shaft 87, the arm 86 constituting one arm of a bell crank lever, the other arm 88 of which is connected by rod or bar 89 to a lever 90 pivoted at 92 and carrying a cam follower roller 91 adapted to engage a rotary 65 cam 93. The cam 93 is so shaped that the follow-up folder 85 will rock about its pivot 87 toward the bottoming drum 41 just behind the folding roller 83, as shown in Fig. 7, and engage the flap 82 prior to the roller 83 leaving the same, thereby 70 insuring that the flap will be folded down before the leading flap 94, i. e. the flap extending forwardly from the score 76 made by the jaw 64, is folded back upon the tube or bag length along this score.

75 Up to now the leading flap 94 is gripped and held down by center gripper 52. By the time the folding of the rear flap is completed the center gripper 52 will have engaged its opening cam 54 so that the front flap will spring upwardly to be 75

engaged by plates 95 while the follow-up folder 85 is still engaging the face of the rear flap 82.

The front flap pick-up and folders 95 are mounted on a shaft 96, rocked by a cam 97 in 5 proper timed relation to the opening of the center gripper 52 so that on continued advance of the bag length the flap will be folded down into position over upon the rear flap of the bag length to bottom the bag, as shown in Fig. 12.

10. In the folding down of the flaps 82 and 94 in the final stages of bottoming the bag, the center gripper jaw 52 is the first to be released, followed by opening of scorer jaws 65 and 64 in the order mentioned.

15. On further advance of the finished bag the front end of the same engages stripping fingers 98 and the bag passes between these fingers and the belt of bottom pressing roller 99, finally passing between this belt, which I will designate 100, 20 and pressing belt 101 to be discharged upon discharge belt 102.

It will be understood that the operations above described are performed on continuously moving bag lengths, the bottoming drum which is rotating continuously being equipped with the necessary number of center grippers 52 and scorers 25 64 and 65 so that as a bag length comes up to the bottoming drum a center gripper is always in position to grip it, and scorer jaws 64 and 65 in position to score it when the drum has carried it to the scoring station.

In the cross scoring mechanism of Figs. 13 and 14 the scoring blade 13' instead of being mounted on an adjustable shaft 14 is mounted in the discs 35 15 on the shaft 16. The cross scoring blade is adapted to be reciprocated vertically in the discs 15 by springs 105 and cam 106. The scoring jaw 17' is cam and spring operated and as in the case of Fig. 2 this jaw 17' cooperates with an abutment 22'. The parts are so timed and the discs 40 15 and 19 are so relatively positioned that as the scoring blade 13' is brought into position to engage a bag length 5 it, that is to say, the scoring blade will be in its outermost position in the discs 45 15, the blade at that time riding on the high part of the cam 106. As the parts reach the position shown in Fig. 13 or on a slightly further advanced position than shown in this figure the cross scoring blade 13' will ride off the high part of the cam 106 so as to be moved inwardly of the discs 50 15 by the action of the spring 105 permitting the jaw 17' to close on the material of the bag length 5 which has been inserted between the jaw 17' and the abutment 22' by the cross scoring blade 55 to allow the jaw to grip the apex of this depressed portion of the bag length, as described in connection with my description of the apparatus shown in detail in Fig. 2. In other words, just as the cross scoring blade 13' is retracted 60 out of the space between the jaw 17' and abutment 22' the jaw will close.

It is to be understood, furthermore, that changes may be made in the details of construction and arrangement of parts hereinabove described without departing from the spirit and scope of my invention.

What I claim is:—

1. In a bag machine, slitting and scoring mechanism, means for operating on the leading end of an advancing bag length after leaving the slitting and scoring mechanism to open the leading end of the bag length and hold-back fingers for holding down the bag length during the opening of the leading end of the bag length. 70

75. 2. In a bag machine, means for continuously

forwarding a bag length, mechanism in the path of the advancing bag length to open the leading end thereof, and hold-back fingers for frictionally retarding the bag length during said opening operation. 5

3. In a bag machine, means for continuously forwarding a bag length, mechanism in the path of the advancing bag length to open the leading end thereof, hold-back fingers between the forwarding mechanism and the opening mechanism, 10 and means for rocking said hold-back fingers into engagement with the bag length during said opening operation frictionally to retard the advance of the bag length.

4. In the making of bags, the process which 15 comprises cross-scoring the bag blanks, and then opening the leading end of the bag blank and folding each wall thereof at said leading end back upon itself along the cross-scoring while frictionally retarding the advance of the bag 20 blank during the said opening and folding operation.

5. In a bag machine, mechanism for operating on the leading end of an advancing bag length or blank comprising a pair of revolvable jaws for 25 gripping one wall of the leading end of the advancing bag length or blank while deflecting the leading end of the other wall out of its normal path of travel, and a revolvable abutment cooperating with said jaws to facilitate restoring of 30 said other wall to its original position after the first wall has been gripped by said jaws.

6. In a bag machine, mechanism for operating on the leading end of an advancing bag length or blank comprising a pair of revolvable jaws one 35 of which is adapted to enter the leading end of the bag length or blank and thereafter to close, thereby to grip one wall of the bag length while effecting a downward deflection of the leading end of the opposite wall of the bag length, and a revolvable abutment below the said jaws engaged by said last mentioned wall while the latter is being deflected to facilitate restoring of 40 said deflected wall to its normal position.

7. In a bag machine, mechanism for operating 45 on the leading end of an advancing bag length or blank, comprising a pair of revolvable jaws one of which is adapted to enter the leading end of the bag length or blank to depress the leading end of the lower wall of the bag blank and grip the upper wall of the bag blank to the other jaw, and a revolvable abutment below the bag length 50 so set with respect to the said jaws that in the deflecting movement of the lower wall of the bag length the bottom face of the lower wall will 55 engage the leading edge of the abutment to the rear of the leading edge of said mentioned wall.

8. In a bag machine, mechanism for opening the leading end of a bag length comprising in combination a rotating bottoming drum, a gripper for securing the end of one wall of the bag length to the bottoming drum, revolvable clamping jaws for gripping the end of the opposite wall of the bag length, rotatable means for carrying said clamping jaws, said rotatable means 65 rotating oppositely to the bottoming drum, whereby the walls of the bag length will be moved away from each other to open the leading end of the bag length, and a plate pivoted on said rotatable means and adapted to move outwardly 70 relatively thereto to force the bag length toward the bottoming drum.

9. In a bag machine, mechanism for opening the leading end of a bag length comprising in combination a rotating bottoming drum, a grip- 75

- per for securing the leading end of one wall of an advancing bag length to the bottoming drum, revolvable clamping jaws for gripping the leading end of the opposite wall of the bag length, 5 rotatable means for carrying said clamping jaws, said rotatable means rotating oppositely to the bottoming drum, whereby the leading end of the bag length will be opened, a plate pivoted on said rotatable means and underlying the wall held by 10 said clamping jaws, and a cam for swinging said plate outwardly toward the bottoming drum to effect corresponding movement of the bag length.
10. In a bag machine, mechanism for opening the leading end of a bag length which has a 15 transverse score intermediate the ends of the bag length and a projecting lip on the leading end of one wall of the bag length, said mechanism comprising a rotatable bottoming drum, a gripper carried thereby adapted to be moved 20 by the drum into gripping engagement with said lip to secure one wall of the bag length to the drum, revolvable clamping jaws, rotatable means carrying said jaws, said rotatable means rotating oppositely to said drum, a plate pivoted on said 25 rotatable means and adapted to engage the cross score in the bag length and to be positively moved toward the bottoming drum at a predetermined instant in the opening of the bag length to insure opening of the bag length along said scored 30 area.
11. In a bag machine, a rotatable bottoming drum, a gripper carried thereby for attachment of the leading end of one wall of an advancing bag length thereto, rotatable means rotating oppositely to said drum and carrying a clamping jaw for the leading end of the other wall of the bag length, thereby to fold this wall back upon itself, means for releasing said clamping jaw, an obstruction in the path of the opened bag length 40 as the same continues to advance for holding the end of the bag length in open position, and a plate curved to the contour of the bottoming drum and movable toward the drum and in the general direction of travel of the bag length 45 thereafter to engage the released bag wall end to flatten the same against the drum.
12. In a bag machine, the combination of a rotary bottoming drum provided with a gripper for attaching the leading end of one wall of a 50 traveling bag length thereto, rotatable means adjacent the periphery of said drum and provided with means for gripping the leading end of the other wall of the bag length, the said rotatable means rotating oppositely to said drum, whereby the leading end of the bag length will 55 be opened and one wall folded back upon itself, a plate adjacent the periphery of the bottoming drum curved to the contour of the drum and adapted to be moved toward the drum and in 60 the direction of advance of the bag length to fold over the opposed sides of the bag length after one wall has been released by said rotat- 65 ing means, revolvable scoring blades for scoring the bag length after the same has been engaged by said plate, and a cam rotatable on the axis of revolution of said scoring blades for controlling the movement of said plate.
13. In a bag machine, a bottoming drum, a 70 scoring jaw, a center gripper and an intermediate scoring jaw cooperating with said drum, and cams for releasing the center gripper, the first mentioned scoring jaw and the last mentioned scoring jaw in the order mentioned.
14. In a bag machine, a folder bar for folding 75 over one flap of a bag bottom, a follow-up folder,

and means for intermittently actuating the same to bring the follow-up folder into engagement with said flap before the same is disengaged by the folder bar.

15. In a bag machine, a folder bar for folding over one flap of a traveling bag bottom, a follow-up folder, means for intermittently actuating the same to swing the follow-up folder into engagement with said flap to the rear of the folder bar before the flap is disengaged by the 10 bar.

16. In a bag machine, a rotatable bottoming drum, a folder bar for folding over one flap of a bag bottom which is traveling with said drum, a pivotally mounted follow-up folder, and means 15 for intermittently actuating the same in the arcuate path into engagement with said flap behind the folder bar before the flap is disengaged by said bar.

17. In a bag machine, a rotatable bottoming 20 drum, a folder bar for folding over the rear flap of a bag bottom which is traveling with said drum, a pivotally mounted follow-up folder, and a cam and spring for rocking said follow-up folder in an arcuate path, into and out of engagement with said flap and timed to swing the follow-up folder into engagement with said flap to the rear of the folder bar and before the flap is disengaged by the bar.

18. In a bag machine, a bottoming drum, ad- 30 justable scoring jaws set into the periphery of said drum, and adjustable filler-in pieces set into said drum behind said jaws.

19. In a bag machine, a rotatable bottoming drum, a gripper carried thereby for attachment 35 of the leading end of one wall of a bag length thereto, rotatable means rotating oppositely to said drum and provided with means for attaching the leading end of the other wall of the bag length thereto whereby the end of the last men- 40 tioned wall will be folded back upon itself, a shaft, a plate carried by said shaft and curved to the contour of said drum, and means for intermittently rotating said shaft in a direction opposite to the direction of rotation of said drum 45 to carry said plate into engagement with the bag length while the plate is traveling in the general direction of the bag length to flatten and smooth the bag length against the drum.

20. In a bag machine, a rotatable bottoming 50 drum, a gripper carried thereby for attachment of the leading end of one wall of a bag length thereto, rotatable means rotating oppositely to said drum and provided with means for attaching the leading end of the other wall of the bag 55 length thereto whereby the end of the last mentioned wall will be folded back upon itself, a shaft, a cam controlled plate carried by said shaft and curved to the contour of said drum, and means for intermittently rotating said shaft in a direc- 60 tion opposite to the direction of rotation of said drum to carry said plate into engagement with the bag length while the plate is traveling in the general direction of the bag length to flatten and smooth the bag length against the drum.

21. In a bag machine, a rotatable bottoming drum provided with means for attaching the leading end of one wall of an advancing bag length thereto, means rotating oppositely to said bottoming drum and provided with means for 70 attaching the leading end of the other wall of the bag length thereto and to fold the same back upon itself, a shaft, a plate carried by said shaft and curved to the contour of said drum, and means for intermittently rotating said shaft in 75

a direction opposite to the direction of rotation of said drum to carry said plate into engagement with the bag length upon the release of one wall thereof by the second-mentioned rotating means 5 to fold the opposed sides of the end of the bag length inwardly and to flatten the same against the drum.

22. In a bag machine, a rotatable bottoming drum provided with means for attaching the leading end of one wall of an advancing bag length thereto, means rotating oppositely to said bottoming drum and provided with means for attaching the leading end of the other wall of the bag length thereto and to fold the same back 10 upon itself, a shaft, a plate carried by said shaft and curved to the contour of said drum, means for intermittently rotating said shaft in a direction opposite to the direction of rotation of said drum whereby to move said plate into engagement with the end of the bag length upon release of the folded bag wall by the second-mentioned rotating means and while said plate is traveling in the general direction of the advancing bag length inwardly toward each other 15 20 and to flatten the same against the drum, and rotatable ironing means thereafter to engage the folded-over edges of the bag length.

23. In a bag machine, slitting mechanism for slitting the leading end of an advancing bag length lengthwise of the bag length, rotatable means provided with a gripper for gripping one wall of the bag length between said slits to attach this wall to said rotatable means, a second rotatable means rotating oppositely to the first 25 mentioned means and provided with a gripper for gripping the other wall of the bag between the slits therein to attach this wall thereto, thereby to fold the leading end of one wall of the bag length back upon itself, a shaft, a plate carried 30 by said shaft and curved to the contour of said drum, and means for intermittently rotating said shaft in a direction opposite to the direction of rotation of said drum to carry said plate into engagement with the bag length upon release of the second mentioned wall and while traveling in 35 the general direction of travel of the advancing bag length to fold the opposite sides of the leading end of the bag length inwardly and along said slits to flatten the same upon the surface 40 of the first mentioned rotating means.

24. In a bag machine, a rotatable bottoming drum provided with a gripper for the attachment thereto of the leading end of one wall of a bag length, means rotating oppositely to the bottoming drum and provided with a gripper for the attachment thereto of the leading end of the other wall of the bag length, whereby as the bag length is advanced the leading end is opened and one wall folded back upon itself, means intermittently rotating in a direction opposite to the 45

direction of rotation of said drum and adapted to engage the leading end of the bag length after the end of the bag length has been released by the second mentioned rotatable means and while traveling in the general direction of travel of the advancing bag length to fold the opposite sides of the bag length inwardly toward each other and to flatten the same against the drum, and ironing means for thereafter engaging the bag length to iron the folded-over sides of the bag length, said ironing means first engaging the bag length behind the leading end of the folded-over sides.

25. In a bag machine, a rotatable bottoming drum provided with a gripper for the attachment thereto of the leading end of one wall of a bag length, means rotating oppositely to the bottoming drum and provided with a gripper for the attachment thereto of the leading end of the other wall of the bag length, whereby as the bag length is advanced the leading end is opened and one wall folded back upon itself, folding means intermittently rotating in a direction opposite to the direction of rotation of said drum and adapted to engage the leading end of the bag length after the end of the bag length has been released by the second mentioned rotatable means to fold the opposite sides of the bag length inwardly toward each other and to flatten the same against the drum, and rotatable ironing means for thereafter engaging the bag length to iron the folded-over sides of the bag length, said ironing means being so constructed that the same first engages the bag length after the leading ends of the turned over sides have passed 35 beyond the axis of rotation of the ironing means.

26. In a bag machine, a rotatable bottoming drum provided with a gripper for the attachment thereto of the leading end of one wall of a bag length, means rotating oppositely to the bottoming drum and provided with a gripper for the attachment thereto of the leading end of the other wall of the bag length, whereby as the bag length is advanced the leading end is opened and one wall folded back upon itself, folding 40 means intermittently rotating in a direction opposite to the direction of rotation of said drum and adapted to engage the leading end of the bag length after the end of the bag length has been released by the second-mentioned rotatable means to fold the opposite sides of the bag length inwardly toward each other and press the same against the drum, and a segmental ironing roller for thereafter engaging the bag length to iron the folded-over sides of the bag length, said roller 45 being so timed that its periphery first engages the face of the bag length to the rear of the leading ends of the turned over sides of the bag length.

ADOLPH POTDEVIN. 60
